SHEEP'S FOOT TAMPER

Ray N. Atkinson, Burlingame, Calif., assignor to Guy F. Atkinson Company, South San Francisco, Calif., a corporation of Nevada

Filed Feb. 18, 1959, Ser. No. 794,043

6 Claims. (Cl. 94—50)

This invention relates generally to soil tampers of the "sheep's foot" type.

Conventional tampers of the above type generally consist of one or more drums rotatably secured to a frame which is tractor drawn or self propelled and which may be adapted to contain water or like ballast. A plurality of tamping feet are mounted upon the peripheral wall of the drum whereby the end of each individual foot applies a compressing or tamping action upon the soil, as the device is moved over a ground surface. For proper tamping action it is generally considered that the length of each tamping foot from the outside surface of the drum, and also that the end area of the tamping foot, should be maintained at nearly their original dimensions. In practice the original proportions are rapidly lost by wear during usage, thus necessitating frequent reconditioning. To facilitate reconditioning, it is common to use a shank attached to the drum, together with a cap socketed upon the end of the shank, which can be replaced when the cap wears beyond the required specifications. The tamping ends of such caps present flat or substantially flat surfaces, whereby the effective tamping action is optimum when the cap is first applied and gradually becomes less effective as the cap wears and the configuration of the cap changes until it has the appearance of being pointed.

In general it is an object of the present invention to provide a tamping foot cap which will provide longer useful life without requiring repair or replacement.

Another object of the invention is to provide a sheep's foot cap which has a novel wear pattern in usage, and which in particular maintains a configuration for good tamping action over a relatively long period of usage.

Additional objects and features of the invention will appear from the following description in which the preferred embodiment has been set forth in detail in conjunction with the accompanying drawing.

Referring to the drawing:

FIGURE 1 is a side elevational view illustrating a conventional type of sheep's foot tamper.

FIGURE 2 is an enlarged cross sectional detail illustrating a sheep's foot cap incorporating the present invention, and applied to a shank.

The conventional tamping equipment shown in FIGURE 1 consists of a drum 10 which is rotatably attached to the frame 11. While the tamper may be self propelled, in most instances the frame 11 is attached to a tractor. The peripheral wall of the drum carries a plurality of spaced tamping feet 12.

As shown particularly in FIGURE 2, each foot consists of a shank 13 which may be a steel casting or forging, and which has its base attached to the wall of the drum as by weld connection 14. A cap 16 is socketed upon the end of the shank, and may likewise be a steel casting or forging. The cap is shown provided with a tapered bore 17, for seating upon the end of the shank. The caps may be attached to the shank by welding or other means, and form effective tamping heads.

In accordance with the present invention, the cap 16 has its tamping end formed by a raised portion or rim 18, which surrounds a central cavity or depression 19. While the head in some instances may be square in section, in this instance it is annular whereby the rim 18 is annular and the recess 19 circular in section. As shown, the radial thickness of the rim 18 is somewhat less than one-

2

half the radius of the head. By way of example, the radius of the head may be 1 1/4 inches, and the rim 5/8 inch thick.

The depression 19 has a substantial depth which preferably is at least equal to the radial thickness of the rim 18. In the proportions illustrated, the depression 19 is substantially greater in depth than the thickness of the rim. For the example specified above, the depression may have a depth of about 1 1/8 inches, and the wall thickness 10 at the bottom of the recess, about 1/2 inch.

The cap construction described above possesses certain novel characteristics. When initially applied, and before there has been any substantial amount of wear, the cap presents a flat end face having an area substantially equal to the cross sectional area of the head at its greatest diameter. The depression 19 becomes packed with soil, and therefore serves as a part of the tamping area, the same as if the depression were not present.

As the end of the cap wears away in usage, the wear 20 occurs completely within the area of the rim 18, because the soil packed in the recess 19, prevents any wear upon the bottom surface 21. Dotted lines 22, 23 and 24 represent progressive wear upon the rim. It will be noted that wear must proceed to the configuration indicated by 25 line 24, before further wear causes a serious decrease in the diameter of the head, in the region of the end of the shank. When wear reaches the dotted line 24, the tamper still presents a relatively unsharpened configuration, particularly when contrasted with the sharpened 30 configuration attained by caps of conventional construction. Therefore, for the period of usage required to wear the cap to the dotted line 24, the cap provides good tamping action. In general the amount of time required to wear the cap to the point indicated by dotted line 24 35 is relatively long compared to a cap of conventional construction, thus minimizing servicing of the equipment, for a given amount of usage.

I claim:

1. A soil tamper of the sheep's foot type, comprising 40 a drum, a plurality of tamping feet carried by said drum, each of said tamping feet including a shank secured to the drum and a metal cap carried by the shank, said cap comprising a body having a tamping end formed with a raised rim, said raised rim defining an open and clear central depression, means securing said cap to said shank, said rim in usage being worn away without substantial wear of the metal forming the bottom of the depression.

2. A soil tamper of the sheep's foot type comprising 45 a drum, a plurality of tamping feet carried by said drum, each of said tamping feet including a shank secured to the drum and a metal cap carried by the shank, said cap comprising a body having a tamping end formed with a raised annular rim, said raised rim defining an open and clear central depression which is circular in section, means securing said cap to said shank, said rim in usage being worn away without substantial wear of the metal forming the bottom of the depression.

3. A soil tamper of the sheep's foot type comprising 50 a drum, a plurality of tamping feet carried by said drum, each of said tamping feet including a shank secured to the drum and a metal cap carried by the shank, said cap comprising a body having a tamping end formed with a raised annular rim, said raised rim defining an open and clear central depression, the said rim having a height at least equal to its thickness, means securing said cap to 55 said shank, said rim in usage being worn away without substantial wear of the metal forming the bottom of the depression.

4. A soil tamper of the sheep's foot type comprising 60 a drum, a plurality of tamping feet carried by said drum, each of said tamping feet including a shank secured to the drum, a head on its outer end, the body of the head

65

having a tamping end formed with a raised annular rim, said raised rim defining an open and clear central depression, means securing said cap to said shank, the rim in usage being worn away without substantial wear of the metal forming the bottom of the depression.

5. A soil tamper of the sheep's foot type comprising a drum, a plurality of tamping feet carried by said drum, each of said tamping feet including a tapered shank secured to the drum, a metal cap carried by the tapered shank, said cap comprising a body having a tamping end and a socket end, said tamping end being formed with a raised rim, said raised rim defining an open and clear central depression, means securing said cap to said shank, said rim in usage being worn away without substantial wear of the metal forming the bottom of the depression, and said socket end being formed with a tapered bore seating upon the end of such shank.

6. A soil tamper of the sheep's foot type comprising a drum, a plurality of tamping feet carried by said drum, each of said tamping feet including a shank secured to

the drum and a metal cap carried by the shank, said cap comprising a body having a tamping end and a socket end, said tamping end being formed with a raised annular rim, said raised rim defining an open and clear central depression which is circular in section, means securing said cap to said shank, said rim in usage being worn away without substantial wear of the metal forming the bottom of the depression, and said socket end being formed with a tapered bore seated on said shank.
